UNITED STATES PATENT OFFICE.

TONY ALEXANDER, OF BOGUE CHITTO, MISSISSIPPI.

GAME-TRAP.

SPECIFICATION forming part of Letters Patent No. 371,727, dated October 18, 1887.

Application filed June 8, 1887. Serial No. 240,639. (No model.)

To all whom it may concern:

Be it known that I, TONY ALEXANDER, of Bogue Chitto, in the county of Lincoln and State of Mississippi, have invented a new and Improved Game-Trap, of which the following is a full, clear, and exact description.

The object of my invention is to provide a new and improved game-trap by which animals passing over the trap are caught around the body or neck without injuring their fur.

The invention consists in the construction and arrangement of various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a front elevation of my improvement in an open or set position. Fig. 2 is a similar view of the same in a closed position. Fig. 3 is a side elevation of the same, and Fig. 4 is a plan view of my improvement in an open or set position.

My improved game-trap A is provided with a longitudinally-extending bottom piece, B, on the top of which is placed the crosswise-extending plate C, through which passes the bolt D, which also passes through the bottom plate, B, and is secured to the same by nut E. On the upper end of the bolt D are provided the ends of the prongs F F', which are straight near their pivoted ends, and then curved outward and upward and slightly sidewise, so that when the prongs F and F' are closed they pass over each other, as shown Figs. 2 and 3.

Over the bolt D passes one end of a spring, G, of U shape, said end resting on the cross-plate C. The other end of the spring G is provided with an enlarged aperture passing freely over the bolt D and over the inner ends of the prongs F and F' when in a closed position. The prongs F and F' are provided with the shoulders F² on their under sides, which limit the opening of the spring G, the upper end of the latter resting, when the

prongs F and F' are in a closed position, against said shoulders F².

On the cross-plate C are hinged the arms H' of the trigger H, provided with the top cross-plate, H², from which extend downward said arms H', and from which also extend laterally the catch-arms H³, each provided near its extreme outer end, on the bottom, with a shoulder, H⁴.

The operation is as follows: When the game-trap is in a closed position, as shown in Figs. 2 and 3, and the operator desires to set the trap, he presses the upper part of the spring G downward until it meets its other end. The prongs F and F' are then swung sidewise into the position shown in Fig. 1, and then the operator swings the trigger H into a horizontal position, so that the outer ends of the catch-arms H³ engage the top edges of the straight parts of the prongs F and F', the shoulders H⁴ of said catch-arms limiting the inward motion of the catch-arms by striking against the outer faces of the prongs F and F'. As soon as the operator now releases the pressure on the upper part of the spring G, the latter exerts its pressure against the inner ends of the prongs F and F', whereby the latter are prevented from closing on account of the catch-arms H³ engaging the top edges of the said prongs F and F'.

It will be seen that as soon as an animal steps on the cross-plate H² of the trigger H the latter will swing downward, thus disengaging the catch-arms H³ from the prongs F and F', whereby the latter are forced shut by the pressure of the spring G, and the animal is caught around its body or neck by said prongs F and F'.

Having thus described my invention, what I claim as new, and desire to secure by Letters Patent, is—

1. In a game-trap, the combination, with the plates B C and the bolt D, secured to the said plates, of the shouldered prongs F F', pivoted at their inner ends to the bolt, the spring G, having one end secured to the said plates and its free end apertured to receive the inner ends of the prongs, and the trigger

H, having arms engaging the prongs, substantially as herein shown and described.

2. In a game-trap, the combination, with the plates B C and the bolt D, secured to the 5 plates, of the curved and pivoted prongs F F', having the shoulders F², the spring G, secured to the said plates and provided with an aperture in its free end for the passage of

the inner ends of the prongs, and the trigger H, provided with the pivot - arms H', the cross-plate H², and the catch-arms H³, substantially as herein shown and described.

TONY ALEXANDER.
